(57) **CLAIM**

The ornamental design for a wheeled assembly for an instrument case as shown and described.

DESCRIPTION

FIG. 1 is an orthogonal view of a wheeled assembly for use with a rollable chordophone case according to our new design;

FIG. 2 is an enlarged orthogonal view of FIG. 1;

FIG. 3 is a front view of the wheeled assembly of FIG. 1; FIG. 4 is an enlarged front view of the wheeled assembly of FIG. 1;

FIG. 5 is a rear view of the wheeled assembly of FIG. 1; FIG. 6 is an enlarged rear view of the wheeled assembly of FIG. 1;

FIG. 7 is a left-side view of the wheeled assembly of FIG. 1;

FIG. 8 is an enlarged left-side view of the wheeled assembly of FIG. 1;

FIG. 9 is a right-side view of the wheeled assembly of FIG. 1;

FIG. 10 is an enlarged right-side view of the wheeled assembly of FIG. 1;

FIG. 11 is a top view of the wheeled assembly of FIG. 1; FIG. 12 is an enlarged top view of the wheeled assembly of FIG. 1;

FIG. 13 is a bottom view of the wheeled assembly of FIG. 1;

FIG. 14 is an enlarged bottom view of the wheeled assembly of FIG. 1;

FIG. 15 is a bottom view of the wheeled assembly of FIG. 1, shown through the environmental structure to allow viewing of the wheel mechanism; and,

FIG. 16 is a bottom view of the opposite side of the wheeled assembly of FIG. 1, shown through the environmental structure to allow viewing of the wheel mechanism.

The broken lines illustrate environment and form no part of the claimed design.
